UNITED STATES PATENT OFFICE.

WILLIAM A. BROWN, OF PHILADELPHIA, PENNSYLVANIA.

EMERGENCY CONVECTION HEATER.

Application filed February 16, 1928. Serial No. 254,718.

My invention relates particularly to improvements to the general class of emergency convection heaters which are attachable to and quickly demountable from existing electric fixtures.

To the above ends, my invention consists of novel means for adjustment whereby the flue surrounding my heating unit, which is preferably of any light transmitting material of low heat conductivity, and its adjuncts of my device may be moved in or out in relation to the face of the fixture on which it is to be mounted, thereby permitting the mounting of my device on any type of existing wall fixture regardless of the distance from the center of the socket or receptacle of the fixture to the face of the fixture, a distance which varies from $1\frac{1}{4}$ " to as much as 3".

My invention further consists of novel means for rigidly holding my device in the desired position in the socket or receptacle to which it has been attached.

My invention further consists of novel means for rigidly holding the socket or receptacle, on which my device has been mounted, in relation to its support, thereby relieving the socket or receptacle of all unnecessary strain and removing all danger of its breaking away from its support or base.

My invention further consists of novel means for ventilating my heating unit core, whereby I reduce the intensity of the heat absorbed and retained by this core from the heating element which it supports, which heat is destructive both to the core and to the socket to which the core is attached.

My invention further consists of a novel deflector-reflector for deflecting the hot air generated by the device in any direction desired, and for diffusing the heat rays of the heating unit.

My invention further consists of novel insulating reflecting means for reflecting the heat rays thrown out by the device, in any direction desired, which also acts to protect walls, furniture etc. from these heat rays when the device is operated adjacent thereto.

My invention further consists of novel means for adjusting the position of my flue and its holder in relation to the bracket which supports my light and heating unit, whereby my flue holder can be brought into a horizontal position and the flue it supports into a

perpendicular position, regardless of any irregularity present in the contour of the various parts comprising my bracket and the means I use in mounting my device on to any existing electric fixture.

My invention further consists of novel means for ventilating my heating unit socket to reduce the destructive absorption of heat by the socket from the unit, thereby prolonging the life of the socket and its various parts, particularly in the case where a pull chain socket is used and the controlling mechanism loses its effectiveness because of the intensity of the heat absorbed by the socket from the heating unit.

For the purpose of illustrating my invention I have shown in the accompanying drawings forms thereof which are at present preferred by me, since they will give in practice satisfactory and reliable results, although it is to be understood that the various instrumentalities of which my invention consists can be variously arranged and organized and that my invention is not limited to the precise arrangement and organization of these instrumentalities as herein shown and described.

Referring to the drawings:

Figure 1, is a vertical section of my device mounted on a short armed bracket with socket support, centralizing bushing, steady washer, supporting nipple, lock nut, bracket base, flue, flue support, heating unit and deflector-reflector in section, the rest of the figure being in elevation, and the sections being taken on line 1—1 of Figure 2.

Figure 2, is a sectional plan view, on a larger scale than Figure 1, the section being taken on line 2—2 of Figure 1.

Figure 3, is a partial side view of my device mounted on a long armed bracket with socket support, centralizing bushing, steady washer, bracket base and flue in section, the rest of the figure being in elevation.

Figure 4, is an exploded view of the several parts used at the base of my device.

Figure 5, is a perspective view of the combination brackets, in detached position showing the adjustable slot at its base.

Figure 6, is a section taken on line 6—6 of Figure 1 of the heating unit core.

Figure 7, is a section taken on line 7—7 of Figure 1 of the heating unit core base.

Figure 8, is a vertical section of my device

with inner flue, the section being taken on the same line as in Figure 1, with the flue support, flue, inner flue, heating unit and bracket base in section, the rest of the figure in elevation. 5

Figure 9, is a vertical section of a modification of my device taken on line 9—9 of Figure 11, the nipples and the junction box, lock nut, bracket, flue support and segmental flue being 10 in section, and the rest of the figure being in elevation.

Figure 10, is a section taken on line 10—10 of Figure 11 the junction box and electric light socket, nipple, bracket, flue support, 15 segmental flue, reflector and deflector being in section, and the rest of the figure being in elevation.

Figure 11, is a sectional plan view of Figures 9 and 10, the section being taken on line 20 11—11 of Figure 9.

Figures 12 and 13 are fragmentary sections of Figure 1.

Figures 14 and 15 are upper and lower plan views of my ventilated socket. 25

Similar numerals of reference indicate corresponding parts in all figures.

1 designates the flue, which is preferably of any light transmitting material of low heat conductivity, and surrounds the heating element 2, which is screwed into the standard socket 3, which is attached to the bracket 4 by means of the nipple 5 and the nut 6. The bracket 4 is attached to the plug cap 7 by means of the nipple 8 which has the shoulder 35 9. The nipple 8, which is held to the plug cap 7 by means of the screw 10, is rigidly held in the desired position in the oval hole 11 by means of the nut 12. The arm 13 of the bracket 4 supports the light socket 14, which 40 holds the bulb 15, by means of the nipple 14. The deflector-reflector 16 is mounted at the top of the flue 1 and is held in position by means of the ears 17. The flue holder 18 which has the arms 19 is held in its adjusted 45 position in relation to the bracket 4 by means of the screws 20 and the nuts 21. The flue holder 18 and the arms 19 can be adjusted and maintained in an infinite number of positions by moving the nuts 21 up or down on the screws 20 thereby permitting the mounting of the flue 1 in a perpendicular position regardless of any manufacturing irregularity present in the bracket 4 and its adjuncts. The plug receptacle 22 which is screwed into 55 the standard socket 23 ready to receive the plug cap 7 is rigidly held in position on the socket 23 by means of the washer 24. The socket 23 which is a part of the fixture 25 is rigidly held in a central position by the solid, 60 split or segmental bushing 26.

In Figure 1, I show a fixture 25 which has a short arm 27, and my entire superstructure has been moved forward in the oval hole 11 to allow the prongs 28 of the plug cap 7 to be 65 inserted in the openings 29 of the plug re-

ceptacle 22. In practice, it has been found that the distance between the center of the socket 23 and the face of the fixture 25, to which my device is to be attached, varies from $1\frac{1}{4}$ " to as much as 3" and without the 70 oval hole 11 for permitting a reasonable in and out movement of my superstructure the application of the device to existing fixtures, for which it is intended, would be limited.

The washer 24 which has the opening 30 to 75 fit the lower portion of the screw plug 22 is necessary in keeping the plug 22 in rigid position on the socket 23, as it has been found in practice that there is a wide variation in the contour of screw plugs, even when made 80 by the same manufacturer, which almost invariably leaves a space between the bottom of the lip 31 of these plugs and the top of the socket 23 to which it has been attached, thereby permitting the entire device to wobble 85 from side to side as this screw plug tends to move inside of the socket 23. Therefore, by the use of a washer 24 of suitable thickness, a rigid assembly between the screw plug 24 and the socket 23 is accomplished, and all 90 movement is eliminated.

The bushing 26, which may be split or in segments, is required to prevent the socket 23 from moving in the fixture 25 when my device has been attached to it. In practice, it 95 has been found that a variable space between the outside walls of the socket 23 and the inside walls of the recessed space of the fixture 25 in which it is mounted is always present, and unless some means, such as the bushing 100 26 which I employ, is used to hold this socket 23 in a rigid upright position, the weight of my device has a tendency to subject it to unnecessary strain, causing the entire device to wobble from side to side with the added 105 danger of severing it from its base.

In Figure 2 it will be clearly seen how the entire superstructure of my device may be moved in and out in the oval hole 11 to permit the mounting of the device on any type 110 of wall fixture regardless of the distance from the center of the socket 23 to the face of the fixture 25.

In Figure 3 I show a fixture that will allow my device to be attached to it with everything 115 concentric. The arm 27 being longer than in Figure 1 permits the nipple 8 and its adjuncts to be locked to the superstructure in its extreme outermost position in the oval hole 11. It is to be understood that the preferred 120 position of my device on the fixture to which it is to be attached, is concentric i. e. that the center of the flue 1 coincides with the center of the socket 23.

Figure 4 is an exploded view of the various 125 parts used in attaching the superstructure of my device to any existing fixture and their relation to each other.

The method of assembling and the functions of these various parts are as follows: 130

The lighting fixture 25 which is of the usual wall type to be found in the average home has the light socket 23 attached to it by means of the nut 25. This lighting fixture and its 5 socket are ready to receive my device as soon as the standard electric light bulb with which it is equipped has been removed. The bushing 26, which may be split or in segments, and which is of different thicknesses is then 10 tightly fitted into the variable space between the inner surface 26a of the fixture 25 and the outer surface of the socket 23 to centralize the socket 23 and to relieve it of all side strain imposed on it by my device. The 15 proper size washer 24, which is supplied in different thicknesses and has the hole 30 in it, is then fitted to the plug receptacle 22, and the plug receptacle is then screwed into the socket 23 insuring a tight fit between the top 20 of the socket 23, the washer 24 and the bottom of the plug receptacle shoulder 31, thereby preventing all movement between the plug receptacle 22 and the socket 23. The use of the washer 24 does away with the expense of 25 manufacturing and supplying several types of plug receptacles 22 having the shoulder 31 of various thicknesses to meet different conditions. The adjustable plug cap 7 which is held in position on the bracket 4 by means of 30 the nut 12 and the nipple 8 is then mounted to the plug receptacle 22 by inserting the blades 28 in the openings 29. The nut 12 has been moved down on the nipple 8 to allow lateral and circular adjustment of the cap 35 7 and its adjuncts in relation to the bracket 4 and its adjuncts. As soon as the bracket 4 and its adjuncts have been revolved around the nipple 8 to bring the oval hole 11 at right angles to the wall and the bracket 4 and its 40 adjuncts have been moved in or out by means of the oval hole 11, so that the flue 1 and the flue holder 18 are in the desired position in relation to the face of the lighting fixture 25, the nut 12 is then moved up and tightened; 45 and the entire device is then rigidly held in its adjusted position indefinitely, ready to be used.

Figure 5 gives a clear idea of the relation of the oval hole 11 to the bracket 4. It will 50 be evident from Figures 1, 2, 3, 4 and 5 that the oval hole 11 to be effective must be at right angles to the face of the existing fixture to which my device is to be attached and to accomplish this the nut 12 is mounted on the 55 nipple 8 to allow it to be moved up and down so that the bracket 4 when the nut 12 is moved down fits loosely on the nipple 8 and may be moved in or out in the oval hole 11 and revolved in either direction around the nipple 8. The necessity of this movement of the bracket 4 around the nipple 8 will be 60 appreciated from the fact that the position of the oval holes 29 in the screw plug 22 after this plug has been screwed down into the 65 socket 23 ready to receive the prongs 28 of the plug cap 7, are never in the same position twice because of irregularities in manufacture and variation in type used, and, without means for adjusting the bracket 4 around the nipple 8, the oval hole 11 would never be 70 in its proper position and the usefulness of the device would be decreased.

Figures 6 and 7 show the method employed in manufacturing the ventilated heating unit core 32 which has the upper vents 33 and the lower vents 34. The advantages of these vents are self evident, in that they permit a current of air to enter the bottom of the core thus tending to keep it cooler than a solid core.

In Figure 8, which is a modification of Figure 1, I show an inner flue 35 around the heating unit 36, which is, in turn, surrounded by the main flue 37, both flues being preferably of a light transmitting material of low heat 85 conductivity. The inner flue 35 is preferably mounted on to the heating unit socket 38 by means of the bracket 39 which has the arms 40 and the ring 41. The socket 38 is mounted on the bracket 42 by means of the nipple 43 and the nut 44. The electric light bulb 45 is mounted in the socket 47 which is attached to the arm 46. The oval hole 48 is the same as in Figure 1 and permits the nipple 49 and its adjuncts to move in and out freely as desired. The nut 50 which is loosened to permit the nipple 49 and its adjuncts to move in and out in the oval hole 48 and to allow the bracket 42 to be revolved around the nipple 49, performs the same function as in Figure 1. The plug cap 51 which is held on the nipple 49 by the screw 52 is the same as described in Figure 1. The flue holder 53 with its arms 54 is mounted on the bracket 42 by means of the screws 55 and the nuts 56. The nuts 56 may be moved 90 up and down on the screws 55 so as to allow the arms 54 and the flue holder 53 to be adjusted in relation to the bracket 42, whereby the flue 37 may be positioned parallel with the wall, regardless of the position of the rest of the device. The plug cap prongs 57 are the same as in Figure 1 and the method of mounting the device on any existing fixture is the same as described for Figure 1.

In Figure 9, which is another modification of my device, I employ two heating units 58 within a segmental flue 59 at the top of which is mounted the deflector-reflector 60. The heating units 58 are attached to the special sockets 61 which have the ventilating holes 61a and are mounted on the bracket 62 by means of the nipples 63 and the nuts 64. The nipple 65 which has the shoulder 66 holds the bracket 62 in rigid position by means of the nut 67, on the junction box 68, which is attached to the plug cap 69 by means of the nipple 70. The bulbs 71 are mounted on the double socket 72 which is also attached to the junction box 68. The adjustable flue holder 73 and the arms 74 are attached to the bracket 100

62 in the same manner as described in Figure 1, by means of the screws 75 and the nuts 76. In this modification of my device, I employ the insulator-reflector 77 which is preferably 5 of mirrored glass and which is held in position by the bracket 78 to reflect the rays of the heating unit in any desired direction and to protect walls, furniture, etc. against the rays of the heating unit when the device is mounted 10 ed. adjacent thereto and high capacity units are used. The segmental flue I employ in this modification allows me to use certain materials in combination with high capacity units which otherwise would not be available 15 unless means were provided such as making the flue in segments, as disclosed, to permit expansion and contraction in heating and cooling without subjecting the material to excess strain. The heating unit core 82 is 20 made with only the lower ventilating openings 83. The deflector-reflector 60 is held in position on the segmental flue 59 by the ears 79 as in Figure 1. The method employed in mounting the device on any existing fixture 25 by means of the plug cap 69 and the prongs 80 is exactly the same as described for Figure 1. The screw 86 holds the nipple 70 in position on the plug cap 69.

Figure 10 shows the location of the oval 30 hole 81 which I employ in all of my devices, the functions of which I have already fully described. In this figure I show how the double socket 72 is mounted on the junction box 68 by means of the nipple 84 and the 35 method employed in holding the insulator-reflector 77 in position by means of the bracket 78 which is attached to the flue holder 73 by the rivets 85.

Figure 11 is a plan view of Figure 9 on line 40 9-9 and of Figure 10 on line 10-10 and shows the position of the insulator-reflector 77, the location of the heating units 58 and the bulb socket 72, the oval hole 81 and the arms 74.

45 In Figures 12 and 13 I show two stages of the adjustment I employ, which has already been fully described, to bring my flue holder 18 into a horizontal position and the flue 1 that it supports into a perpendicular position, regardless of the position of the bracket 4 and 50 its adjuncts. By moving the nut 21 up or down on the screw 20 an infinite number of positions of the arms 19 and the flue holder 18 can be obtained and held.

55 In Figures 14 and 15 I show the method I employ to ventilate the heating unit socket 61 by means of the holes 61^a, which allow currents of cool air to circulate throughout the 60 length of the socket, thereby reducing the destructive absorption of heat by the socket from the unit and prolonging the life of the socket and its various parts.

In a great many cases it is advantageous to 65 employ both the heating unit, or units and the light, or lights but in many cases arising

in practice the lights can be dispensed with, and the construction will still be within the spirit and scope of my invention.

It will be apparent to those skilled in this 70 art that my present invention does not involve any complicated wiring, and that such wiring as is required can be done by anyone with ordinary training or by the layman.

The various embodiments of my invention disclosed and claimed herein are assembled 75 and controlled so as to give heat or light or both heat and light as desired.

It will now be apparent that I have devised a novel and useful construction of an emergency convection heater which embodies features of advantage enumerated as desirable in the statement of the invention and the above description, and while I have in the present instance shown and described preferred embodiments thereof which have been found in practice to give satisfactory and reliable results, it is to be understood that the same are susceptible of modification in various particulars without departing from the spirit or scope of the invention or sacrificing any of its advantages.

Having thus described my invention what I claim as new and desire to secure by Letters Patent, is:—

1. In a quick demountable heating and 95 lighting lamp, a flue, an electric heating unit surrounded by said flue, an electric light bulb mounted in proximity to said flue, a support for said flue, heating unit and bulb, said heating unit and bulb being so assembled and controlled as to give heat or light or both simultaneously or independently, means for attaching said support and its adjuncts to any existing electric fixture, and said support having means to allow lateral and circular adjustment of said attaching means on said support.

2. In a quick demountable heating and 100 lighting lamp, a flue, an electric heating unit surrounded by it, an electric light bulb mounted in proximity to said flue, a support for said flue, heating unit and bulb, said heating unit and bulb being so assembled and controlled as to give heat or light or both simultaneously or independently, a deflector-reflector mounted at the top of said flue, means for attaching said support and its adjuncts to any existing electric fixture, and said support having means to allow lateral and circular adjustment of said attaching means on said support.

3. In a quick demountable heating and 110 lighting lamp, a flue, an electric heating unit surrounded by it, an electric light bulb mounted in proximity to said flue, a support for said flue, heating unit and bulb, said heating unit and bulb being so assembled and controlled as to give heat or light or both simultaneously or independently, an insulator-reflector mounted outside of said flue, means for attaching said support and its adjuncts to any existing electric fixture, and said sup- 120 125 130

port having means to allow lateral and circular adjustment of said attaching means on said support.

4. In a quick demountable heating and lighting lamp, a flue, an electric heating unit surrounded by it, an electric light bulb mounted in proximity to said flue, a support for said flue, heating unit and bulb, said heating unit and bulb being so assembled and controlled as to give heat or light or both simultaneously or independently, a deflector-reflector mounted at the top of said flue, an insulator-reflector mounted outside of said flue, means for attaching said support and its adjuncts to any existing electric fixture, and said support having means to allow lateral and circular adjustment of said attaching means on said support.

5. In a quick demountable heating and lighting lamp, a flue, an electric heating unit surrounded by said flue, an electric light bulb mounted in proximity to said flue, a support for said flue, heating unit and bulb, said heating unit and bulb being so assembled and controlled as to give heat or light or both simultaneously or independently, means for attaching said support and its adjuncts to any existing electric fixture, said attaching means being mounted on said support to allow relative movement between said attaching means and said support, in combination with an adjustable flue holder assembled on said support to allow it to be moved in relation to said support to maintain the flue held by said holder in a perpendicularly disposed position regardless of the position of said support and its adjuncts.

6. In a quick demountable heating and lighting lamp, a flue, an electric heating unit surrounded by said flue, an electric light bulb mounted in proximity to said flue, a support for said flue, heating unit and bulb, said heating unit and bulb being so assembled and controlled as to give heat or light or both, simultaneously or independently, a pronged cap adjustably mounted on said support, a plug receptacle, a socket for said plug receptacle, and means for rigidly holding said receptacle to said socket and for rigidly supporting said socket in a perpendicularly disposed position.

7. In a quick demountable heating and lighting lamp, a flue, an electric heating unit surrounded by said flue, an electric light bulb mounted in proximity to said flue, a support for said flue, heating unit and bulb, said heating unit and bulb being so assembled and controlled as to give heat or light or both, simultaneously or independently, a pronged cap adjustably mounted on said support, a plug receptacle, a socket for said plug receptacle, means for rigidly holding said receptacle to said socket and for rigidly supporting said socket in a perpendicularly disposed position, in combination with an adjustable flue holder for maintaining the flue held by said holder in

a perpendicularly disposed position regardless of the position of the other parts of the device.

8. In a quick demountable convection heater, a flue, an electric heating unit surrounded by said flue, a support for said flue and unit, means for attaching said support and its adjuncts to any existing electric fixture, and said support having means to allow lateral and circular adjustment of said attaching means on said support.

9. In a quick demountable convection heater, a flue, an electric heating unit surrounded by said flue, a support for said flue and unit, in combination with means for maintaining the flue in a perpendicularly disposed position regardless of the position of said support and its adjuncts.

10. In a quick demountable heating and lighting lamp, a flue, an electric heating unit surrounded by said flue, an electric light bulb mounted in proximity to said flue, a support for said flue, heating unit and bulb, said heating unit and bulb being so assembled and controlled as to give heat or light or both, simultaneously or independently, and means to effect the alignment of said flue in a vertically disposed position regardless of the position of other parts of the lamp.

11. In a quick demountable convection heater and lighting lamp, a flue, an electric heating unit surrounded by said flue and comprising resistance wire held in position by a ventilated core of suitable material, a support for said flue and unit and means for attaching said support and its adjuncts to any existing electric fixture, in combination with means to effect the alignment of said flue in a vertically disposed position.

12. In a quick demountable heating and lighting lamp, a plurality of flues surrounding a plurality of electric heating units, and a plurality of electric light bulbs mounted in proximity to said flues, a support for said flues, heating units and bulbs, said heating units and bulbs being so assembled and controlled as to give heat or light or both, simultaneously or independently, means for attaching said support and its adjuncts to any existing electric fixture, and said support having means to allow lateral and circular adjustment of said attaching means on said support.

13. In a quick demountable convection heater, a flue, an electric heating unit surrounded by said flue and comprising resistance wire held in position by a ventilated core of suitable material and mounted on a ventilated socket, a support for said flue, unit and socket, a deflector-reflector mounted at the top of said flue and an insulator-reflector mounted outside of said flue, a pronged cap adjustably mounted on said support, a plug receptacle, a socket for said plug receptacle, means for rigidly holding said receptacle to

said socket and for rigidly supporting said socket in a perpendicularly disposed position, in combination with an adjustable flue holder for maintaining the flue held by said holder in a perpendicularly disposed position regardless of the position of the other parts of the device.

14. In a quick demountable heating and lighting lamp, a flue, an electric heating unit 10 surrounded by said flue and comprising resistance wire held in position by a ventilated core of suitable material and mounted on a ventilated socket, an electric light bulb mounted in proximity to said flue, a support for said 15 flue, heating unit and bulb, said heating unit and bulb being so assembled and controlled as to give heat or light or both, simultaneously or independently, a deflector-reflector mounted at the top of said flue and an insulator-reflector 20 mounted outside of said flue, a pronged cap adjustably mounted on said support, a plug receptacle, a socket for said plug receptacle, means for rigidly holding said receptacle to said socket and for rigidly supporting 25 said socket in a perpendicularly disposed position, in combination with an adjustable flue holder for maintaining the flue held by said holder in a perpendicularly disposed po-

sition regardless of the position of the other parts of the device.

15. In a quick demountable heating and lighting lamp, a plurality of flues, a plurality of electric heating units surrounded by said flues and comprising resistance wire held in position by ventilated cores of suitable material and mounted on ventilated sockets, a plurality of electric light bulbs mounted in ventilated sockets in proximity to said flues, a support for said flues, heating units and bulbs, said heating units and bulbs being so assembled and controlled as to give heat or light or both, simultaneously or independently, a deflector-reflector mounted at the top of said flues, an insulator-reflector mounted outside of said flues, a pronged cap adjustably mounted on said support, a plug receptacle, a socket for said plug receptacle, means for rigidly holding said receptacle to said socket and for rigidly supporting said socket in a perpendicularly disposed position, in combination with an adjustable flue holder for maintaining the flues held by said holder in a perpendicularly disposed position regardless of the position of the other parts of the device.

WILLIAM A. BROWN.
